UNITED STATES PATENT OFFICE.

ROBERT L. PAGE, OF GREENVILLE, MISSISSIPPI.

TRAIN-DISPATCHING APPARATUS.

Application filed September 8, 1925. Serial No. 55,099.

The present invention relates to train dispatching and wayside signalling systems and apparatus, and aims to provide a novel and approved apparatus of that kind whereby the train dispatcher may keep fully informed as to the movements of trains in the division or section of which he has charge, and may set signals at signal points or locations for controlling traffic, as well as being able to communicate with the trainmen. The apparatus may also be used as a system of communication, either privately or otherwise, orally by telephone or by telegraphic printed matter, such as between employees and officials, or between officials; and the apparatus may also be used for the conveyance of commercial telegraphic and telephonic communications such as are transmitted by the public telephone, telegraph and radio companies.

The present apparatus provides for the following functions: First, the dispatcher is informed when a train approaches a signal location. Second, the dispatcher is also informed as to the particular train that is approaching the signal location. Third, the dispatcher may then set the signal or signals at such signal location according to traffic conditions or other circumstances. Fourth, the trainmen may communicate by telephone with the dispatcher to receive instructions. Fifth, the dispatcher may operate a printing telegraph ticker or other instrument for producing a written order or instructions for the train crew. Sixth, the dispatcher has similar information about, control of and communication with all control station sets of the division or section within his jurisdiction.

A more specific object is the provision of an apparatus whereby the dispatcher may conveniently control and set one or more signals at a control location or station, for establishing or changing signals according to traffic conditions from information obtained as to the movements of trains, so as to expedite traffic.

With the foregoing and other objects in view, which will be apparent as the de-

scription proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 is a diagrammatical view of the apparatus showing only one control location set,

Fig. 2 is a plan view of one of the switch actuators showing the switch open,

Fig. 3 is a plan view of said actuator showing the switch closed, and

Fig. 4 is a fragmentary view of said switch.

The line wires 7 and 8 are extended along the right of way throughout the length of the division or section of road under the supervision of the dispatcher, and constitute the telephone circuit such as is used in the well-known train dispatching apparatus. Said wires lead from a selector key 9 in the dispatcher's office by means of which the dispatcher has control of any number of selectors (of well known construction and operation) connected in multiple with the wires 7 and 8, the receiver 10 and transmitter 11 in the dispatcher's office being connected in the telephone circuit.

At the approach to each control station or location there is a transmitter 12 connected in series with a pair of contacts 13 of a switch device 14 and with the wires 7 and 8, whereby when the contacts 13 are bridged the transmitter 12 is connected in the telephone circuit in order that the dispatcher may receive (by the receiver 10) sounds impressed on the transmitter 12. The transmitter 12 is used for impressing in the telephone circuit characteristic or identifying sounds or audible signals to convey information to the dispatcher.

The switch device 14, the details of which will be described more fully hereinafter, is controlled by an electromagnet 15 which is connected by the wires or conductors 17

with a selector 16, a battery 18 being disposed in one of the conductors 17 to furnish current for the magnet 15. The selector 16 is connected by the conductors 19 with

5 the wires 7 and 8.

The dispatcher is informed of the approach of a train toward a control location. Thus, an electric repeating phonograph 20 or other suitable signal transmitting device

10 is disposed adjacent to the transmitter 12 and the record, sound producing means or indication of the phonograph or device is such as to produce a characteristic sound, audible signal or indication, which may be

15 heard or received in the receiver 10 when the sounds or indications given out by the phonograph 20 are transmitted by the transmitter 12 to the telephone circuit. The sound, audible signal or indication produced

20 by the phonograph 20 is an identification of the particular control station or location, in order to inform the dispatcher that a train is approaching the particular control location. The phonographs 20 at different ap-

25 proaches to control locations have records, sound producing means or indications for producing different sounds, audible signals or indications, in order that they may be differentiated by the dispatcher, even

30 though several signals or indications may be received simultaneously due to several trains approaching different control locations simultaneously.

The phonograph 20 is disposed in a circuit 21 including the battery 22 and a pair of contacts 23 of a switch device 24 (similar to the switch device 14), and said switch device 24 is controlled by an electro-magnet 25 connected by the conductors 27 with a

40 selector 26 which, like the selector 16, is connected by the wires or conductors 19 with the telephone wires 7 and 8. A battery 28 is disposed in one of the conductors 27 to furnish current for the magnet 25.

45 At the approach to the control location, at a suitable distance from the wayside signals, a third rail or ramp 29 is disposed on the track, between the rails as shown, and the train or vehicle carries a wheel 31 or

50 other contact to roll or move over the ramp 29, said contact wheel 31 being connected electrically with car wheels 5 of the train, so as to be connected electrically with the rails 6. The ramp 29 is connected by the conduct-

55 tor 30 with one of the conductors 17 and one of the conductors 27, and a conductor 30' connects one of the rails 6 with the other conductors 17 and 27. Consequently, when

60 the contact wheel 31 moves over the ramp, the magnets 15 and 25 are energized so that the switch devices 14 and 24, which are normally open, are operated to bridge the contacts 13 and 23. The circuit includes

65 ramp 29, conductor 30, corresponding conductors 27 and 17, magnets 25 and 15 and

batteries 28 and 18 (the magnet 15 and battery 18 being in parallel relation with the magnet 25 and battery 28), the conductor 30', corresponding rail 6, wheels 5 and contact wheel 31. The magnets 15 and 25 are thus energized whenever a train, carrying a contact wheel or member 31, approaches the corresponding control location or wayside signals. The switch 14 bridging the contacts 13 will connect the transmitter 12 in the telephone circuit, and the contacts 23 being bridged will close the circuit of the electric phonograph or indicator 20, which will continue to operate as long as its circuit remains closed, so that the distinctive sounds, signals or indications are received by the transmitter 12 and impressed in the telephone circuit so as to be heard in the receiver 10 by the dispatcher. This will indicate to the dispatcher that a train is approaching the particular control location.

The switch devices 14 and 24 are of similar construction as illustrated in detail in Figs. 2, 3 and 4. Each of said devices includes a switch 32, pivoted, as at 33, on a base 34, and having an angularly extending arm 35. The switch is of the knife-blade type as shown to wedge between the pair of contacts 13 or 23 for closing the corresponding circuit, although any suitable switch may be used. A catch 37 is pivoted, as at 38, on the base 34 to engage the switch 32 and hold it in open position, and a retractile coiled spring 39 is connected to the catch 37 and arm 35, and has a tendency to swing the switch 32 to closed position and to move the catch 37 into engagement with the switch. Said catch has a hook or lug 40 to engage the switch 32 and hold the switch in open position, as seen in Fig. 2, and when the catch is disengaged from the switch, the spring 39 swings the switch to closed position, as seen in Fig. 3, with the hook 40 bearing against the end of the switch. Electromagnet 15 or 25 is mounted on the base 34 and controls an armature lever 42 fulcrumed on the base, as at 42', a spring 43 moving the lever 42 away from the arm 35 of the switch. A spring leaf 44 is secured to the catch 37 and has a hook 45 and cam 46 at the free end thereof, with the leaf 44 projecting toward the lever 42 and arm 35. The lever 42 carries a finger 47 to engage the hook 45 when the lever 42 is swung by its attraction to the electromagnet 15 or 25.

The switch 32 is alternately closed and opened by the successive intermittent energizations of the magnet. Thus, with the parts arranged as shown in Fig. 2, with the catch 37 holding the switch 32 in open position, the attraction of the lever 42 to the magnet will result in the finger 47 catching in the hook 45 and pulling the leaf 44 so as to swing the catch 37 to releasing position,

thereby releasing the switch 32 and the spring 39 swings the switch 32 to closed position. When the magnet is deenergized, the spring 43 returns the lever 42 to normal position. The catch 37 being released by the lever 42 will bear against the end of the switch 32, as seen in Fig. 3, and the leaf 44 is swung so that the hook 45 is out of the path of movement of the finger 47. 5 When the lever 42 is swung to move the catch 37 to releasing position, the lever contacting with the arm 35 will hold the switch 32 in open position until the magnet is deenergized and the lever 42 returned to normal position, as seen in Fig. 2, the switch 32 moving to closed position as the lever 42 returns to normal position. The next time the magnet is energized to swing the lever against the pressure of the spring 43, the 10 finger 47 moves past the hook 45, and the lever contacts with the arm 35 and swings the switch 32 to open position. The catch 37 will immediately snap into engagement with the switch, to hold the switch in open position. The leaf 44 being moved to the position shown in Fig. 2 will bring the cam 46 in front of the finger 47 so that when the magnet is deenergized and the lever 42 returned, the finger 47 moving under the cam 20 46 will spring the leaf 44 so that the hook 45 will snap in rear of the finger 47, to the position shown in Fig. 2. Thus, with the successive intermittent energizations of the magnet the switch 32 is alternately closed 25 and opened, and will remain in either position until the magnet is again energized.

The dispatcher is also informed as to the identification of the particular train which is approaching the control location 30 announced by the phonograph 20. Any suitable device may be used for this purpose. As shown, a pair of ramps 48 and 49 is mounted on the track at the approach to the control location, being disposed beyond the ramp 29. Said ramps 48 and 49 are connected by the respective conductors 50 and 51 with a telegraph ticker 52 which is disposed adjacent to the transmitter 12. Thus, when said transmitter 12 is connected 35 in the telephone circuit by the switch device 14, the telegraphic code of the ticker 52 may be transmitted to the telephone circuit so as to be heard by the dispatcher. A battery 53 is located in the conductor 51 to supply 40 current for energizing the ticker 52, and the train or vehicle carries the control shoes or members 54 and 55 to slide over the respective ramps 49 and 48. The vehicle or train equipment includes a conductor 56 connecting the shoe 54 with a contact or brush 57, which co-operates with the contact wheel or drum 58 that is connected by a conductor 59 with the shoe 55. The wheel 58 has contact portions or segments thereon to 45 engage the contact 57 in succession when the

wheel is rotated, for producing "dots and dashes" in telegraphic code, in order to identify the particular train, each train having a contact wheel or drum 58 for producing a specific identification signal, so that 70 the dispatcher may identify the train. The wheel 58 is connected to an electric motor 60 to be operated by the motor, and said motor is connected by the conductors 61 and 62 with the shoe 55, which has the insulation 63 between the conductors 61 and 62 so as to normally open the motor circuit. The battery 64 is located in the conductor 62 to furnish the current for operating the motor when the insulation 63 is bridged. 75 Thus, when the shoe 55 moves over the ramp 48, the insulation 63 is bridged, thereby connecting the conductors 61 and 62, so that the motor 60 is operated to rotate the contact wheel 58. The shoes 54 and 55 moving over 80 the ramps 49 and 48, respectively, will also complete the telegraphic signalling circuit of the train and track, part of the circuit being on the train and part on the track. Thus, the ticker is on the track while the 85 telegraphic transmitter, comprising the contact wheel 58, contact 57 and motor 60 is located on the train. The circuit includes the battery 53, ramp 49, shoe 54, conductor 56, contact 57, contact wheel 58, conductor 90 59, shoe 55, ramp 48 conductor 50, ticker 52, and conductor 51. Thus, as the telegraphic transmitter on the train is operated by the motor 60, while the shoes 54 and 55 move over the ramps, the ticker 52 is operated to give a telegraphic signal, which 95 may be repeated inasmuch as the ramps 48 and 49 may be of any suitable length. The wheel 31 passes onto the ramp 29 before the shoes 54 and 55 pass onto the ramps 49 and 100 48, respectively, so that soon after hearing the sound or signal given by the phonograph 20, indicating the particular station or location, the ticker 52 will be heard to identify the particular train. The dispatcher will 105 therefore have information both as to the particular station or signal location which the train is approaching and the particular train that is approaching such location, in order that the dispatcher will be informed 110 115 as to the movement of trains, and so that the wayside signals may be set and controlled accordingly.

The wayside signals may be of any approved kind. As shown, at each control 120 location there are electric signal lamps 65, 66 and others according to the character of signals desired and the number of tracks. Said lamps are disposed in signal circuits. Thus, the circuit of the lamp 65 includes a 125 conductor 67, a pair of contacts 71 of a switch device 72, conductor 70, battery 69 or other source of electrical energy, and conductor 68. The circuit of the lamps 66 includes a conductor 67, a pair of contacts 130

71' of a switch device 72', and the conductor 70, battery 69 and conductor 68 which may be common to all of the signal circuits. The switch devices 72 and 72' are of the same type as the switch devices 14 and 24 and are controlled by the respective electromagnets 73 and 73'.

There may be any number of signal lamp circuits. Thus, there may be one or more 10 lamps or signals for each track of a number of tracks. Lamps of different colors may be used for giving clear, caution, danger and similar signals, or different numbers of lamps or combinations of colors may be used 15 in the different circuits according to prevailing wayside signal practice. As shown, there is a single lamp 65 in the first circuit and two lamps 66 in the second circuit for purpose of illustration. One switch device is 20 used for each signal circuit and there may be any number of such devices and signals controlled thereby according to the requirements or circumstances.

The signal devices of the control station 25 sets are controlled by a single electrical circuit in addition to the telephone circuit, said single circuit including the wire 8 of the telephone circuit and a third line wire 74. At each control station a conductor or wire 30 75 is connected to the wire 8 and to one terminal of each of the magnets 73, 73' of the signal control devices, and a conductor or lead wire 76 is connected to the line wire 74 and to a commutator 78. A telegraph key 77 is connected in the telegraph or make and break circuit including the line wires 8 and 74, and means are provided whereby the key 77 may be connected in succession with the several magnets 73, 73' of any control station, said means of the control location set shown including the commutator 78 for connecting the magnets 73, 73' of the control station in succession in the telegraph or signal control circuit. The commutator 40 45 78 includes a disk or wheel 79 operated through any suitable gearing by an electric motor 80, said disk 79 having a contact lug or brush 81 to engage in succession a series of contact segments 82 which are connected by the conductors 83 with the magnets 73, 73'. Thus, the first contact segment 82 is connected to the first magnet 73, the second segment 82 is connected to the second magnet 73' and so on. The battery 84 is connected 50 55 between the key 77 and the wire 8. When the contact brush 81 engages the first segment 82, the telegraph key 77 may be connected in circuit with the first magnet 73, such circuit including the line wire 74, telegraph key 77, battery 84, line wire 8, conductor 75, magnet 73, first conductor 83, first segment 82, contact brush 81, disk 79 and conductor 76. By operating the telegraph key 77 the magnet 73 in such circuit may be

energized to either open or close the switch 65 device 72.

The motor 80 is started under the control of the dispatcher. Thus, a selector 85 is connected to the telephone wires 7 and 8, and when properly controlled by the selector 70 key 9 will connect wires 86 and 88. The wire 88 and a wire 87 are connected to the line wires 8 and 74, respectively, of the telegraph circuit, and an electromagnet 89 is connected to the conductor 87 and to the 75 wire 74. The conductors 86 and 87 have contacts 91 normally bridged by a switch 92. Therefore, when the selector 85 is controlled to connect the conductors 86 and 88 for several seconds, this connects the 80 magnet 89 between the wires 8 and 74 of the telegraph circuit in order to give the dispatcher an opportunity to start the motor 80. This is done by closing the telegraph key 77, which completes an electric circuit 85 including the battery 84, key 77, line wire 74, magnet 89, conductor 87, contacts 91 and switch 92, conductor 86, conductor 88 and line wire 8. The magnet 89 being energized will reverse the switch 92, moving said 90 switch away from the contacts 91 so as to immediately deenergize the magnet 89, and the switch is brought against the contacts 93 in the circuit 94 of the motor 80 including the battery or source of electrical energy 95. The motor 80 therefore operates to rotate the disk 79, and when the disk has made one complete revolution, the contact brush 81 engages the switch 92 and swings said switch back to normal position 100 105 away from the contacts 93 and against the contacts 91. The motor is therefore stopped when the disk 79 has completed its revolution.

It is apparent that the electromagnet 89 105 may be controlled directly from the selector 85 the same as magnets 15, 25, 111 and 121 are controlled from the respective selectors 16, 26, 112 and 122.

In order that the dispatcher may be informed when the successive magnets 73, 73' of a control station are connected in the telegraph circuit, an electric bell 96 or other audible signal device is provided, being disposed adjacent to a transmitter 101 located 110 at the control or signal location so that the bell or signal may be heard over the telephone circuit. One terminal of the bell 96 is connected by a conductor 97 with the battery 98 and conductor 76, and the other terminal of the bell is connected by a conductor 99 with contacts 100 disposed in advance 115 of the contact segments 82. Just before the contact brush 81 engages a contact segment 82 the brush 81 will engage the corresponding contact 100. This completes the circuit of the bell 96, including the battery 98, conductor 76, disk 79, brush 81, corre- 120 125

- sponding contact 100, conductor 99, bell 96 and conductor 97. The bell or signal being heard over the telephone circuit for the first time will inform the dispatcher that 5 the telegraph key 77 is being connected in circuit with the magnet 73. The bell 96 rings just prior to the connection of each magnet 73, 73' of a control station set in the telephone circuit.
- 10 The transmitter 101 is automatically connected in and disconnected from the telephone circuit by the closing and opening of the motor circuit 94. Thus, one terminal of the transmitter 101 is connected to the wire 15 7 and a conductor 102 leads from the other terminal of said transmitter to one of a pair of contacts 103, the other of which is connected to the conductor 75 leading to the wire 8. An electromagnet 105 in the motor 20 circuit 94 is energized whenever said circuit is closed thereby closing a switch 104 against the contacts 103 to connect the transmitter 101 in the telephone circuit (by way of the conductor 102, contacts 103, switch 25 104 and conductor 75) whenever the motor 80 and the commutator are in operation.
- A printing telegraph ticker 106 may be provided at each control station for printing on a tape or sheet a written message or 30 order. The ticker 106 is adapted to be connected in the telegraph circuit. Thus, one terminal of the ticker 106 is connected by the conductor 106' with the wire 8, and a conductor 107 is connected to the wire 74, 35 with a pair of contacts 109 between the conductor 107 and the ticker 106. Battery 108 is disposed in the conductor 106'. A switch device 110, similar to the switch devices 14 and 24, is used to bridge the contacts 109 and 40 connect the ticker in the circuit of the wires 8 and 74. The device 110 is controlled by an electromagnet 111 connected to a selector 112 which is connected to the wires 7 and 8. The dispatcher may therefore connect the 45 ticker 106 in the telegraph circuit for transmitting a message or order, by controlling the selector 112 by the key 9, to close the switch device 110 and bridge the contacts 109. Then, when the message has been 50 transmitted the selector 112 may be controlled to open the switch device 110 and disconnect the ticker 106 from the telegraph circuit. Should the conductor, engineer or any other person desire to communicate with 55 the dispatcher, a telephone transmitter 115 and receiver 114 are provided at the control station, and the connection thereof in the telephone circuit is controlled by a switch device 120, similar to the devices 14 and 24, the device 120 being controlled by an electromagnet 121 connected to a selector 122 which is connected to the wires 7 and 8. The receiver 114 and the transmitter 115 are connected by a suitable telephone set 116 60 with the wire 8 and a conductor 117 having
- the battery 119 therein. The device 120 when in closed position connects the conductor 117 with a conductor 118 connected to the wire 7, thereby connecting the telephone set in the telephone circuit. A call key 124 70 and battery 125 are connected to the wire 8 and a fourth line wire 126, in order that the conductor or other person may signal the dispatcher. A selective annunciator 123 is located in the dispatcher's office, and is connected to the wires 8 and 126 so as to signal to the dispatcher the particular control station which is calling (similar to an ordinary call system).
- If so desired, automatic train control 80 means may be used to prevent the train from passing signals set against it. Any suitable devices may be used for this purpose. As shown, electromagnets 127 and 128 are disposed in the signal circuits in series with the 85 respective lamps 65 and 66, and are mounted on the track, for operating armatures or switches 129 and 130 carried by the train. The switches 129 and 130 are disposed in stick circuits 131 and 132, respectively, including 90 the electromagnets 133 and 134 and switches 135 and 136, respectively. The electromagnets 127 and 128 have permanent magnet cores, the flux of which is neutralized when the coils are energized by the closing of the 95 signal circuits so that the armatures or switches will not be affected in passing the signal location. However, when either or both of the electromagnets 127 and 128 are de-energized, the attempt of the train to pass 100 will result in the corresponding switch or both switches 129 and 130 being opened by the permanent magnet flux of the cores, to open one or both of the circuits 131—132. When either of said circuits is opened to drop the 105 switch 135 or 136 the circuit will remain open, and the switches 135 and 136 may control the air brakes, power or other means for retarding or stopping the train according to 110 the signals set against it. The switches 135 and 136 may be under lock and key so that they cannot be restored except by an authorized person. However, various well known or suitable train control devices may be used 115 in connection with the signal devices to obtain automatic retarding or stopping of the train if the engineer does not obey the signals set against him.
- The operation is as follows: When a train 120 approaches a signal location, the contact wheel 31 moving over the ramp 29 will result in the magnets 15 and 25 being energized so that the switch devices 14 and 24 are operated to bridge the contacts 13 and 23. The 125 phonograph 20 is therefore operated, and the transmitter is connected in the telephone circuit, and the dispatcher hearing the distinctive sounds or audible signals in the telephone circuit will be informed that a 130

train is approaching the particular control station. Then, the shoes 54 and 55 passing over the ramps 49 and 48 will signal from the train to the train dispatcher, by telegraphic code, the particular train that is approaching the signal location. The circuit of the ticker 52 is opened and closed by the wheel or device 58 on the train so that the ticker transmits the identification code of the train. The motor 60 and wheel 58 are only operated while the shoe 55 is moving over the ramp 48 so that the insulation 63 is bridged. Being informed that a train is approaching a specified signal location, and being also informed as to the particular train, the dispatcher may then set the signals accordingly, depending on traffic conditions. When desired, the phonograph 20 may be stopped by energizing the magnet 25 again through control of the selector 26 by the selector key 9, to open the switch device 24. It is thus possible to cut out the phonograph when the dispatcher has heard same, in order to avoid confusing sounds or signals. The transmitter 12 is likewise readily cut out of the telephone circuit by controlling the selector 16 from the key 9 to open the switch device 14. The switch devices 14 and 24 must be opened by energizing the magnets 15 and 25 by way of the selector key 9 after the train has passed, and, before the next train approaches, in order that control of the magnets 15 and 25 from the ramp 29 will close said switch devices.

To set the signal of the control station which the train is approaching, the selector key 9 is operated by the dispatcher to control the selector 85 of the particular station, so as to connect the magnet 89, in the telegraph circuit including the battery 84, telegraph key 77, wire 74, magnet 89, conductor 87, contacts 91 and switch 92, conductor 86, conductor 88 and wire 8. By closing the key 77 the magnet 89 is energized to move the switch 92 against the contacts 93. At the same time, the switch 92 is moved away from the contacts 91 to open the circuit of the magnet 89. The switch 92 remains in either of its reversed positions until moved, either by a positive impulse due to the energization of the magnet 89 or to the engagement of the brush or lug 81 with the switch 92, and when the switch 92 bridges the contacts 93 it closes the circuit 94 of the motor 80, so that the motor is started and will rotate the disk 79 of the commutator 78. The brush 81 engaging the first contact 100 will ring the bell 96 and the transmitter 101 being connected to the telephone circuit by the closing of the switch 104 by the energized magnet 105 will enable the dispatcher to hear the bell, thus giving him a signal that the commutator 78 is in operation. The brush 81 engages the first contact segment 82 and connects the first magnet 73 of the signal control devices in the telegraph circuit. This circuit includes the battery 84, telegraph key 77, conductor 74, conductor 76, disk 79, brush 81, first segment 82, first conductor 83, first magnet 73, conductor 85 and wire 8. If after the first ringing of the bell 96 is heard, the dispatcher desires to change the first signal, he closes the key 77 so as to energize the magnet 73 of the first signal control device, to open or close the circuit of the lamp 65 and electromagnet 127 as the case may be. The lamp 65 may therefore be lighted or extinguished. Then, as the brush 81 leaves the first segment 82 it engages the second contact 100, again ringing the bell 96 and informing the dispatcher that the next signal control connection is being made. When the brush 81 engages the second segment 82 the magnet 73' of the second signal control device is connected in the telegraph circuit, and the dispatcher may then set the second signal if he wishes. In this manner, as the disk 79 makes a complete revolution the magnets 73, 73' of the several signal relays are connected in succession in the circuit of the telegraph key 77 so that the dispatcher may set the several signals according to traffic conditions and other circumstances. The signal lamps or other signal devices may be used for signals of all different sorts for train movements, not only to indicate clear, caution and danger conditions, but also the tracks or sidings which the train should take. The signals may also be used to notify the engineer or conductor to get into communication with the dispatcher, and a single control station may also control the signals of any number of tracks.

Should the dispatcher desire, as herein-before described, the ticker 106 may be used for producing a printed message or order, and if the engineer, conductor or other person desires to communicate with the dispatcher, the call key 124 is operated whereby the annunciator 123 in the dispatcher's office will inform the dispatcher of the particular control station which is calling. The dispatcher may then, by the control of the selector 122, connect the transmitter 115 and the receiver 114 of the control station set in the telephone circuit so that conversation may be had between the dispatcher and the person calling. The transmitter 115 and receiver 114 are cut out of the telephone circuit by opening the switch device 120 when the magnet 121 is again energized by the operation of the selector 122.

In order that the dispatcher may know the position of the switches 14, 24, 72, 72', et al. he may have a chart before him indicating the positions of the various switches. It is also possible to use suitable indicators in the dispatcher's office, one for each switch, to indicate whether the switch is on or off. It is also possible to have miniature sets in the

dispatcher's office corresponding to the various control location sets, with suitable indicators, so that the dispatcher may note at a glance the condition of the various devices 5 of the different control locations. It will therefore be apparent that provision may be made in order that the dispatcher will have intelligent control of the various devices. In fact, each control location set may be duplicated, in miniature, in the dispatcher's office, 10 at least the essential elements thereof, in order that the dispatcher may observe, through suitable indicators, the condition of the control elements and other devices 15 throughout the division under his control.

Other devices may be used in lieu of the phonograph 20 and telegraph ticker 52 in order to transmit information to the dispatcher in any suitable manner concerning 20 the approach of trains to control locations and identifications of the trains and control locations, and the other devices of the apparatus may also be of any suitable kind.

For protection at isolated places against 25 malicious persons or trespassers, casings may be used to house the devices and may also protect the devices from the elements during adverse weather conditions.

Having thus described the invention, what 30 is claimed as new is:—

1. A train dispatching system comprising a telephone circuit including a dispatcher's receiver, and train-controlled means at the approach to each of a plurality of control 35 locations of the track operable when a train passes to transmit distinctive telephonic sound waves to said circuit.

2. A train dispatching system comprising a telephone circuit including a dispatcher's 40 receiver, train-controlled means at the approach to each of a plurality of control locations of the track operable when a train passes to repeatedly transmit distinctive telephonic sound waves to said circuit, and 45 means controlled by said circuit and selectively controlling the firstnamed means to stop such transmission of sound waves to the circuit.

3. A train dispatching system comprising a telephone circuit including a dispatcher's receiver, distinctive telephonic sound wave producing means at the approach to each of a plurality of control locations of the track, and train-controlled means for each 55 of said means operable when a train passes to bring the corresponding firstnamed means into operation and to connect it with said circuit for transmission of the sound waves to said circuit.

4. A train dispatching system comprising a telephone circuit including a dispatcher's receiver, a distinctive telephonic sound wave producer for each of a plurality of locations of the track, train-controlled means at the 60 approach to each of said control locations

operable when a train passes and controlling the corresponding sound wave producer to bring said sound wave producer into operation, and also operable to connect said sound wave producer with said circuit for the 70 transmission of the sound waves to said circuit, and means selectively controlled by said circuit for stopping said sound wave producers.

5. A train dispatching system comprising 75 a telephone circuit including a dispatcher's receiver, a transmitter for each of a plurality of control locations of the track, a phonograph cooperable with each transmitter, and train-controlled means for connecting the corresponding transmitter to said circuit and bringing the companion phonograph into operation when a train approaches a control location.

6. A train dispatching system comprising 85 a telephone circuit including a dispatcher's receiver, a transmitter for each of a plurality of control locations of the track, a repeating phonograph cooperable with each transmitter, train-controlled means for connecting 90 the transmitter of a control location to said circuit and bringing the corresponding phonograph into operation when a train approaches such control location, and means controlled by said circuit and selectively controlling said transmitters and phonographs to disconnect the transmitters from the circuit and to stop the phonographs.

7. A train dispatching system comprising 100 a telephone circuit including a dispatcher's receiver and a dispatcher's selector key, in combination with a set of devices for the approach to each of a plurality of control locations of the track, including an electrically operable phonograph, an electrically 105 operable switch device controlling said phonograph; means for transmitting the sounds from said phonograph to said circuit, train-controlled means controlling said switch device for bringing the phonograph into operation when a train passes, and a selector controlled by said circuit and controlling said switch device to control the phonograph from said circuit and selector key.

8. A train dispatching system comprising 115 a telephone circuit including a dispatcher's receiver and a dispatcher's selector key, of a set of devices for the approach to each of a plurality of control locations of the track, 120 including a transmitter, an electrically operable phonograph, an electrically operable switch device controlling said phonograph, an electrically operable switch device for connecting the transmitter in said circuit, train-controlled means controlling both of said switch devices for connecting the transmitter in said circuit and bringing the phonograph into operation when a train passes, and selectors controlled by said circuit and 130

individually controlling said switch devices.

9. A train dispatching system comprising an electrical circuit including a dispatcher's indication receiver, a train-carried identifying indication transmitter operable at a substantially uniform speed independently of the speed of movement of the train, and means at the approach to a control location of the track cooperable with said transmitter 10 when the train passes for transmitting the indications to said circuit.

10. A train dispatching system comprising a telephone circuit including a dispatcher's receiver, a train-carried identifying code transmitter operable at a substantially uniform speed independently of the speed of movement of the train, a sound producer at the approach to a control location of the track, and cooperable with said transmitter 15 when the train passes for the control of said sound producer from said transmitter, and means for transmitting sounds of said sound producer to said circuit.

11. A train dispatching system comprising an electrical circuit including a dispatcher's receiver, a train-carried identifying telegraph code transmitter operable at a substantially uniform speed independently of the speed of movement of the train, a ticker, 20 at the approach to a control location of the track, cooperable means on the train and track for the control of said ticker by said transmitter when the train passes, and means for transmitting the indications of said 25 ticker to said circuit.

12. A train dispatching system comprising a telephone circuit including a dispatcher's receiver, a train-carried identifying code transmitter, a sound producer at the approach to a control location of the track, cooperable means on the train and track for the operation of said sound producer by said transmitter when the train passes, a transmitter cooperable with said sound producer, 40 and means controlled by said circuit for connecting the lastnamed transmitter with and disconnecting it from said circuit.

13. A train dispatching system comprising an electrical circuit including a dispatcher's 50 indication receiver, a train-carried identifying indication transmitter, means at the approach to a control location of the track including cooperating elements on the train and track for transmitting the indications to said circuit, and operating means for said 55 transmitter controlled by said elements to operate the transmitter when said elements are cooperating.

14. A train dispatching system comprising an electrical circuit including a dispatcher's receiver, a train-carried identifying telegraph code transmitter, a ticker at the approach to a control location of the track, cooperable means on the train and track including cooperable elements for the control 60

of said ticker by said transmitter when a train passes, means for transmitting the indications of said ticker to said circuit, and means for operating said transmitter controlled by said elements to bring the transmitter into operation when said elements are cooperating. 70

15. A train dispatching system comprising an electrical circuit including a dispatcher's indication receiver, a train-carried identifying indication transmitter operable independently of the speed of movement of the train, means controlling said transmitter and operable to bring it into operation when the train approaches a control location of 80 the track, and means on the track cooperable with said transmitter for transmitting the indications to said circuit.

16. A train dispatching system comprising a telephone circuit including a dispatcher's receiver, a telephone sound transmitter for each of a plurality of control locations of the track, switch devices for connecting said transmitters with and disconnecting them from said circuit, train controlled means 85 controlling said devices for automatically connecting the corresponding transmitter with said circuit when a train approaches a control location, train controlled means for impressing distinctive train location and 90 train-identifying sound waves in said transmitters when trains approach the corresponding control locations, and selective means controlled by said circuit and controlling 95 said switch devices. 100

17. A train dispatching system comprising a telephone circuit including a dispatcher's indication receiver, a telephone transmitter at each of a plurality of control locations of the track arranged for transmitting telephonic sound waves to said circuit, and train-controlled means for producing distinctive sound waves in said transmitters as trains approach the corresponding control 105 locations. 110

18. A train dispatching system comprising a telephone circuit including a dispatcher's indication receiver, and train-controlled means operable at a substantially uniform speed independently of the speed of movement of the train for transmitting distinctive indications to said circuit when trains approach a plurality of control locations of the track so as to identify the particular control locations, and to transmit other distinctive indications to said circuit to identify the particular trains. 115 120

19. A train dispatching system comprising a telephone circuit including a dispatcher's receiver, train-controlled means at the approach to each of a plurality of control locations of the track operable at a substantially uniform speed independently of the speed of movement of the train when a train passes to transmit distinctive indica- 125 130

tions to said circuit to identify the particular control location, and train controlled means operable at a substantially uniform speed independently of the speed of movement of the train when a train approaches one of said control locations to transmit distinctive indications to said circuit to identify the particular train.

20. A train dispatching system comprising an electrical circuit including a dispatcher's receiver, train-controlled means at the approach to each of a plurality of control locations of the track operable at a substantially uniform speed independently of the speed of movement of the train when a train passes a point of the track to transmit distinctive indications to said circuit to identify the particular control location, and train controlled means including cooperable elements on the track and train operable at a substantially uniform speed independently of the speed of movement of the train for transmitting other distinctive indications to said circuit at a point beyond the aforesaid point to identify the particular train.

21. A train dispatching system comprising a telephone circuit including a dispatcher's receiver, transmitters adapted to transmit sound waves to said circuit, train-controlled distinctive sound producers for different control locations of the track cooperable with said transmitters and brought into operation when a train approaches the particular control location, other sound producers cooperable with said transmitters, and a train-carried identifying code transmitter cooperable with the lastnamed transmitters when the train approaches the corresponding control locations, for identifying the train.

22. A train dispatching system comprising an electrical circuit including a dispatcher's indication receiver, train-controlled means at the approach to each of a plurality of control locations of the track operable at a substantially uniform speed independently of the speed of movement of the train when a train passes to transmit distinctive indications to said circuit to identify the particular control location, a train-carried identifying indication transmitter operable at a substantially uniform speed independently of the speed of movement of the train, and means at each of said approaches cooperable with said transmitter when the train passes for transmitting the indications to said circuit.

23. A train dispatching system comprising a telephone circuit including a dispatcher's receiver and a dispatcher's selector key, transmitters for different control locations of the track, electrically operable distinctive sound producers cooperable with said transmitters for identifying the particular con-

trol locations, electrically operable switch devices controlling said sound producers, electrically operable switch devices for connecting said transmitters in said circuit, train-controlled means controlling both of said devices at each control location for connecting the corresponding transmitter in said circuit and bringing the corresponding sound producer into operation when a train passes, a ticker at each of said approaches cooperable with said transmitter, a train-carried identifying telegraph code transmitter, cooperable means on the train and track for the control of said tickers by said telegraph code transmitter when the train passes, and selectors controlled by said circuit and individually controlling said switch devices.

24. A train dispatching system including a plurality of signal devices at a control location of the track, a control circuit including a dispatcher's key, and means operable for connecting all of said devices in succession in said circuit for the individual control thereof by said key.

25. A train dispatching system comprising a plurality of signal devices at a control location of the track, a control circuit including a dispatcher's key, and means operable for connecting all of said devices in succession in said circuit for the control of said devices one at a time by said key.

26. A train dispatching system including a plurality of signals at a control location of the track, switch devices controlling said signals, a control circuit including a dispatcher's key, and a commutator device operable for connecting all of said switch devices in succession in said circuit for the individual control of said switch devices by said key.

27. A train dispatching system including a plurality of signal devices at each of a plurality of control locations of the track, an electrical circuit having a dispatcher's selector key, a signal control circuit including a dispatcher's signal control key, means at each of said control locations operable for connecting all of the corresponding signal devices in succession in the signal control circuit for the individual control of said devices by the signal control key, and selectors in the firstnamed circuit controlling the lastnamed means.

28. A train dispatching system including a plurality of signals at each of a plurality of control locations of the track, an electrical circuit including a dispatcher's selector key, a signal control circuit including a dispatcher's signal control key, switch devices at each of said control locations controlling said signals, a commutator device at each of said control locations operable for connecting the corresponding switch devices in succession in said signal control circuit for

the control of the signals by said signal control key, and selectors in the firstnamed circuit controlling the commutator devices.

29. A train dispatching system including a plurality of signals at each of a plurality of control locations of the track, an electrical circuit including a dispatcher's selector key and a dispatcher's receiver, a signal control circuit including a dispatcher's signal control key, switch devices at each of said control locations controlling said signals, a commutator device at each of said control locations operable for connecting the corresponding switch devices in succession in said signal control circuit for the control of the signals by said signal control key, selectors in the firstnamed circuit controlling the commutator devices, and means controlled by each commutator device for producing indications in the firstnamed circuit before each switch device is connected in said signal control circuit.
30. A train dispatching system including a plurality of signal devices at a control location of the track, a dispatcher's signal control key, a dispatcher's selector key, and means controlled by said selector key and operable by a single completed operation for electrically connecting the signal control key individually in succession with said signal devices.

31. A train dispatching system including a plurality of signal devices at a control location of the track, a dispatcher's signal control key, a dispatcher's selector key, and a commutator device controlled by said selector key and operable by a single completed operation for electrically connecting the signal devices in succession with said signal control key.

32. A train dispatching system comprising a telephone circuit including a dispatcher's receiver and a dispatcher's selector key, train-controlled means for transmitting distinctive indications to said circuit when trains approach a plurality of control locations of the track so as to identify the particular control locations, and to transmit other distinctive indications to said circuit to identify the particular trains, a set of signal devices at each control location, a control circuit including a dispatcher's signal control key, a selector for each set of signal devices controlled by said telephone circuit, and means controlled by each selector for automatically connecting the signal devices of the corresponding set in succession with the control circuit for individual control of said signal devices by the signal control key.
33. A train dispatching system comprising a telephone circuit including a dispatcher's receiver and a dispatcher's selector key, train-controlled means for transmitting distinctive indications to said circuit when trains approach a plurality of control locations of the track so as to identify the particular control locations, and to transmit other distinctive indications to said circuit to identify the particular trains, a set of signal devices at each control location, a control circuit including a dispatcher's signal control key, a selector for each set of signal devices controlled by said telephone circuit, and means controlled by each selector for automatically connecting the signal devices of the corresponding set in succession with the control circuit for individual control of said signal devices by the signal control key.

tions of the track so as to identify the particular control locations, and to transmit other distinctive indications to said circuit to identify the particular trains, a set of signal devices at each control location, a control circuit including a dispatcher's signal control key, a selector for each set of signal devices controlled by said telephone circuit, means controlled by each selector for automatically connecting the signal devices of the corresponding set in succession with the control circuit for the individual control of said signal devices by the signal control key, and other selectors controlled by said telephone circuit and controlling the firstnamed means to stop such transmission of indications to said telephone circuit.

34. A train dispatching system comprising an electrical circuit including a dispatcher's printing transmitter, printing devices at different locations of the track, and means for selectively connecting said devices with said circuit.

35. A train dispatching system comprising two electrical circuits, one including a dispatcher's selector key and the other including a dispatcher's printing transmitter, printing devices at different locations of the track, and selectors controlled by the firstnamed circuit for selectively connecting said devices with the secondnamed circuit.

36. A train dispatching system comprising an electrical circuit including a dispatcher's selector key, another electrical circuit including a dispatcher's printing transmitter, printing devices at different locations of the track, switch devices for connecting said printing devices with the secondnamed circuit, and selectors controlled by the firstnamed circuit and controlling said switch devices.

37. A train dispatching system comprising a telephone circuit including a dispatcher's indication receiver, a telephone transmitter at each of a plurality of locations of the track arranged for transmitting telephonic sound waves to said circuit, and means controlled at distances from said transmitters for selectively connecting said transmitters with said circuit.

38. A train dispatching system comprising a telephone circuit including a dispatcher's indication receiver, a telephone transmitter at each of a plurality of locations of the track arranged for transmitting telephonic sound waves to said circuit, and train controlled means for connecting said transmitters with said circuit when trains approach and pass said locations.

39. A train dispatching system comprising a telephone circuit including a dispatcher's indication receiver, a telephone transmitter at each of a plurality of locations of the track arranged for transmitting telephonic sound waves to said circuit, and

means controlled at the location of the dispatcher's indication receiver for selectively connecting said transmitters with said circuit.

5 40. A train dispatching system comprising a telephone circuit including a dispatcher's indication receiver, a telephone transmitter at each of a plurality of locations of the track arranged for transmitting telephonic sound waves to said circuit, means

controlled from said circuit for selectively connecting said transmitters with said circuit and means at the location of said dispatcher's indication receiver and connected to said circuit to control the aforesaid means 15 selectively.

In testimony whereof I hereunto affix my signature.

ROBERT L. PAGE.
